Primary Examiner — Janice Patyk(74) *Attorney, Agent, or Firm* — BROOKS KUSHMAN P.C.(57) **CLAIM**

The ornamental design for a speaker assembly as shown and described.

DESCRIPTION

FIG. 1 is a front perspective view of a speaker assembly, showing my new design;

FIG. 2 is a left side view of FIG. 1;

FIG. 3 is a front view of FIG. 1;

FIG. 4 is a right side view of FIG. 1;

FIG. 5 is a rear view of FIG. 1;

FIG. 6 is a top view of FIG. 1; and,

FIG. 7 is a bottom view of FIG. 1.

The broken lines in the figures illustrate the portions of the speaker assembly and form no part of the claimed design. The dot-dash broken lines immediately adjacent to the claimed areas in the views represent the boundaries of the design and form no part thereof.
